UNITED STATES PATENT OFFICE.

DOBRIVOJE BOŽIĆ, OF BELGRADE, YUGOSLAVIA.

ACCELERATOR.

Application filed November 5, 1923. Serial No. 672,965.

To all whom it may concern:

Be it known that I, DOBRIVOJE Božić, a subject of the King of Yugoslavia, residing at Belgrade, Yugoslavia, have invented new and useful Improvements in Accelerators, of which the following is a specification.

In order to avoid dangerous reactions which are liable to be experienced when a train is braked rapidly, the depression or drop of pressure in the train pipe should be propagated as rapidly as possible from the point of control to the extremity of the train.

This desideratum is realized by allowing the air to escape from the train pipe either into the atmosphere or into the brake cylinder or into isolated chambers by way of so-called accelerators. Accelerators which exercise what may be designated a total action produce an excessive drop of pressure in the train pipe, resulting in useless waste of the air and in a braking effect of constant rapidity; accelerators which exercise a partial and repeated action cannot be relied on to operate with certainty.

An accelerator of one of the best known types operates as follows:

The rapid pressure drop in the train pipe effects the movement of a piston located above an isolated chamber filled with air at the initial pressure, bringing about the opening of a distributor unitary with said piston; the action of the accelerator being interrupted by emptying the isolated chamber.

With this principle as a basis, notwithstanding that many efforts have been made to solve the problem, practical success has not hitherto been realized. Certainty of operation is only obtained when the opening and closing of the distributing member do not take place after the opening or closing of the closed chamber or space.

In the following specification there is described by way of example a construction embodying this principle in which at the end of its travel the accelerator piston meets a stop and a balanced valve in the interior of the piston continues its travel under the influence of its inertia and opens the isolated chamber to exhaust; return and premature closure being prevented by a current of air which issues from the isolated chamber and impinges on a cap unitary with the valve until the moment when the distributing member closes in consequence of the equalization of pressure.

The evacuation and closure of the isolated chamber may be effected at the same time as the closure of the distributing member, there being employed two valves arranged to close simultaneously.

Two constructions embodying the invention are illustrated in Figs. 1 and 2 of the accompanying drawings.

Referring to Fig. 1, there is formed in the body 1 of the accelerator a passage 8 connected to the main train pipe and communicating by way of passages 71 and 72 with the chamber 73 above the accelerator piston 74 which separates this chamber from the chamber 75. The stem 76 of the piston penetrates the base of the chamber 75 and enters the passage 71, closing with the valve 77 at the end of said stem the passage 78 leading to the atmosphere or to the brake cylinder. A spring 79 urges the piston 74 downwards. In the interior of the piston and of its stem is seated a valve 80 the stem 81 of which enters the cavity 82 and is formed as a piston, serving to balance the valve when the cavity 82 is connected with the passage 71 by way of the port 83. The part of the cavity 82 between the valve 80 and its piston communicates with the chamber 75 by way of the port 84 and with the isolated space 73 when the valve 80 is lifted from its seat, the upper part of the valve forming a large cap and obstructing almost completely the passage 86.

In the second construction shown diagrammatically in Fig. 2, the valve 800 forms a part of the stem 76 of the piston 74 and has its seat in the body 1. The said valve closes simultaneously with the valve 77. The valve 800 controls the exhaust from the chamber by way of the passage 870, the port 840 and the passage 820 leading to the chamber 73 and to the channel 71 by way of the port 830.

The operation is as follows:

When the main train pipe is filled with air the air passes by way of the passages 8, 71 and 72 into the chamber 73 and leaks therefrom into the chamber 75.

When slight or slow pressure drops are set up in the train pipe, the air from the chamber returns by the same route and the accelerator does not come into action. When the diminution in pressure is effected with sufficient rapidity and is of sufficient amount, the enclosed air thrusts the piston 74 up-

wardly, so that the valve 77 opens and air passes from the train pipe into the passage 78.

In the first construction, the piston 74 is thrust upwardly until it abuts on the stop, when, in consequence of its inertia, the balancing valve 80 is unseated and the air passes from the isolated space into the chamber 73; the accelerator piston 74 under the influence of the spring 79 and of the excess pressure acting on the valve 77 commences to descend and closes the valve.

The valve 80 can only engage its seat again when the air current coming from the isolated space is directed against its cap and suppressed.

In the second construction, the two valves open simultaneously. During the ascent of the piston the pressures above and below the piston balance one another. The piston then commences to descend and closes the two valves simultaneously.

Having now fully described and ascertained my said invention and the manner in which it is to be performed, I declare that what I claim is:—

1. The combination, with a train-pipe normally containing fluid under pressure, of a casing, a chamber within said casing, a piston within said chamber dividing the same into upper and lower compartments, a spring acting to depress said piston, and a hollow stem for said piston extending down through the bottom wall of said lower compartment, and being formed at its lower end as a valve to control a port in the bottom wall of the casing, said hollow stem having ports communicating with said lower compartment through which the air therein can escape into said hollow stem and thence into the upper compartment on the operation of the device, and also having ports communicating with a passage located between the chamber and the casing which passage is connected with the train-pipe, and a branch of which passage communicates with the upper compartment of the chamber.

2. The combination, with a train-pipe normally containing fluid under pressure, of a casing, a chamber in said casing, a piston within said chamber dividing the same into upper and lower compartments, a spring acting to depress said piston, a hollow stem for said piston extending down through the bottom wall of said lower compartment and being formed at its lower end as a valve to control an exhaust port in the wall of the casing and having ports communicating with said lower compartment, and other ports communicating with a passage located between the chamber and the

casing, which passage communicates with the train-pipe, a branch of which passage also communicates with the upper compartment, a balancing valve located in said hollow stem, a stem for said valve, and a piston formed on said rod.

3. The combination, with a train-pipe normally containing fluid under pressure, of a casing, a chamber in said casing, a piston within said chamber dividing the same into upper and lower compartments, a spring acting to depress said piston, a hollow stem for said piston extending down through the bottom wall of said lower compartment and being formed at its lower end as a valve to control an exhaust port in the wall of the casing and having ports communicating with said lower compartment, and other ports communicating with a passage located between the chamber and the casing communicating with the train-pipe, a branch of which passage also communicates with the upper compartment, a balancing valve located in said hollow stem, a rod for said valve, and a piston formed on said rod, said first-mentioned ports in the hollow piston stem being adapted to permit the escape of air from said lower compartment into said hollow stem and thence into the upper compartment on the opening of the balancing valve.

4. The combination, with a train-pipe normally containing fluid under pressure, of a casing, a chamber in said casing, a piston within said chamber dividing the same into upper and lower compartments, a spring acting to depress said piston, a stop for bringing said piston to rest before it reaches the top of the upper compartment, a hollow stem for said piston extending down through the bottom wall of said lower compartment and being formed at its lower end as a valve to control an exhaust port in the wall of the casing and having ports communicating with said lower compartment, and other ports communicating with a passage located between the chamber and the casing communicating with the train-pipe, a branch of which passage also communicates with the upper compartment, a balancing valve located in said hollow stem, a rod for said valve, and a piston formed on said rod, said first-mentioned ports in the hollow piston stem being adapted to permit the escape of air from said lower compartment into said hollow stem and thence into the upper compartment on the opening of the balancing valve.

In testimony whereof I have signed my name to this specification.

DOBRIVOJE BOŽIĆ.
